UNITED STATES PATENT OFFICE.

JOHN W. DOUGHERTY, OF STEELTON, PENNSYLVANIA.

FURNACE-CHARGING DEVICE.

1,024,623.

Specification of Letters Patent.

Patented Apr. 30, 1912.

Application filed September 3, 1910. Serial No. 580,463.

To all whom it may concern:

Be it known that I, JOHN W. DOUGHERTY, a citizen of the United States, residing at Steelton, in the county of Dauphin and 5 State of Pennsylvania, have invented certain new and useful Improvements in Furnace-Charging Devices; and I do hereby declare the following to be a full, clear, and exact description of the invention, such as 10 will enable others skilled in the art to which it appertains to make and use the same, reference being had to the accompanying drawings, and to letters or figures of reference marked thereon, which form a part of this 15 specification.

My invention relates to the reduction of ores in shaft furnaces, and more particularly to the reduction of such ores, specifically iron ores, that are accompanied with 20 much fines, and my invention consists in feeding the flue dust, or it may be the fine ore itself, into the blast or reduction furnace during its operation, below the stock line but above the crucible.

25 Heretofore the flue dust or fines have been introduced into the blast furnace at or above the stock line, or into the crucible thereof, with the blast. In both of these methods of 30 operation there are serious objections; in the first of them it is difficult to retain the fines at the stock line, they being almost immediately blown out again, and in the second the introduction of ore into the molten bath, slag or metal, impairs the quality of 35 the metal produced, by abstracting too much heat from the molten bath and by imperfect reduction of the ore or flue dust introduced.

By my invention I introduce the flue dust or fines below the stock line at points where 40 the fine ore will be held in the furnace by a certain thickness of the charge above the point of introduction, and preferably the introduction takes place at a point of the furnace where there is sufficient heat to 45 sinter the fine mass as soon as it is introduced, thereby converting the dust or fines at once into a state or physical condition in which they cannot be blown out.

Referring to the accompanying drawings, 50 wherein like parts are similarly designated—Figure 1 is an elevation of a blast furnace, partly in section, wherein the fines or flue dust are fed into the furnace; Fig. 2 is an elevation of a portion of the furnace 55 at right angles to Fig. 1; Fig. 3 is a plan view; Figs. 4 and 5 are detail sectional

views of two forms of mechanism for forcing in charges of flue dust or fines, the first being intermittent in its action and the second continuous in its action.

As the most trouble is experienced in the reduction of fine iron ores, such as Mesaba ores, I have shown my invention in connection with a blast furnace A having a suitable furnace charging mechanism, indicated 60 at B, supplied by a skip hoist C, or otherwise. Above the furnace A or on top of it, and above the furnace charging apparatus I place the flue dust collector 2, having a conical bottom 3. The down-comer 4 for 65 the gas enters the top of the dust collector 2 and extends, preferably, but not necessarily, centrally into the same some distance below the top of the collector, as shown in Fig. 1. The gas emanating from the charge 70 in the furnace A enters a pipe or pipes 5, four such being shown in the drawings, and passes through the discharge portions of 75 pipes 5, shown as branch pipes 6 to discharge tangentially into the collector near 80 the top of the dust collector and above the entrance to the down-comer 4, so that the dust and gas will have imparted to them a 85 centrifugal movement, by means of which the dust is more effectually separated from the gas, so that the gas will pass to the down-comer with comparatively little dust. The pipes 5 are provided at their top with 90 bleeders 7 mounted on levers 8 provided with adjustable counter-weights 9.

Connected to the dust collector 2 at or 95 near the bottom thereof, at preferably diametrically opposite points, are flue dust delivery pipes, 10 and 11, that extend in a spiral line downward and about half way around the furnace, and discharge by inclined ends 12 and 13 into a bin or receptacle 14 for storing an excess of the flue dust. The pitch or incline of the spiral portions of the pipes 10 and 11 is sufficient 100 to cause the dust to travel therethrough by gravity. Descending from the spiral portion of the pipes 10 and 11 are substantially vertical supply pipes or pockets 15 that supply the dust to the charging devices 18 or 105 18^a, Fig. 4 or 5. If the charging device Fig. 4 is used, the flue dust drops from pipe 15 in front of the plunger 19 into pipe 20 to which the pipe 15 is connected at its lower end. The plunger is provided with a 110 rod 21 on the end of which is a piston 22 operating in an air cylinder 23. This cyl-

inder is supplied with motive fluid from a suitable conduit by a pipe 24 through an automatic steam or air valve 27, of any well known type. The pipe 20 is in alignment with a passage 25 through the walls of the furnace A. A bracket 26 secured to the casing a of the furnace supports the mechanism.

The action of the mechanism shown in Fig. 4 is intermittent, the piston 22 actuating the plunger 19 to and fro to push the dust that has fallen in front of it into pipe 20 and passage 25, so that small portions or charges of dust are pushed one behind the other until they enter the furnace below the stock line or at the reducing zone, where they either are held by the mass of the furnace charge above, or at once become coherent sufficiently to be able to be sustained in the furnace under all conditions of operation of the furnace. The stroke of the piston and plunger is such that the plunger will never have movement in excess of its length, as otherwise the dust in pipe 15 would fall behind the piston and either prevent its operation or force the head of the plunger casing off. To effectually prevent this the plunger cylinder may be provided with an opening 33 through which any dust accidentally accumulating behind the plunger will be discharged, although I have not found this to be absolutely necessary if the parts are well fitted.

In Fig. 5 the screw conveyer 28 replaces the plunger of Fig. 4, and this conveyer extends beneath the discharge end of the flue-dust supply pipe 15, into pipe 20. The shaft 29 of the screw is provided with a bevel gear wheel 30 actuated by a similar bevel gear wheel 31 on a continuously driven shaft 32. The operation of this modified form of flue-dust charging device is continuous, as the screw 28 which is continuously rotated from shaft 32 will constantly deliver or force the flue-dust, delivered to it from pipe 15, through the passage 25. The flue-dust caught in the dust catcher 2 descends by gravity through the spiral pipes 10 and 11 and falls into the supply pipes 15, which act as pockets to retain or trap quantities of the flue-dust and supply it to the charging devices 18 or 18^a. In case the charging devices cannot get rid of the flue-dust fast enough as it descends through pipes 10 and 11, as when an excess of dust is produced by a slip in the furnace charge, then the excess will pass by way of pipes 12 and 13 to the storage receptacle, from which it is taken and charged into the furnace in the regular way through the hopper, or it may be charged into the dust catcher through a suitable door therein. The flue-dust caught in the dust collector 2 is returned to the furnace again without allowing the reduced iron contained in it to become re-oxidized,

thereby saving the heat that under other conditions would be required to reduce the dust that would have become re-oxidized. Should the dust catcher become filled with dust for any reason, and prevent the gas from passing through it and the down-comer 4, the bell-bleeder valves 7 will automatically release the gas coming off from the top of the furnace.

I claim—

1. The combination with a reducing furnace; of a dust collector mounted above the furnace, means to deliver flue dust from said furnace tangentially into said collector, pipes connected at the bottom of the collector into which said collector discharges by gravity, and means to force charges of flue-dust into the furnace below its stock line and supplied with dust from said pipes.

2. The combination with a reducing furnace; of a dust collector, means to discharge the dust therefrom in a continuous stream, pockets to entrap the dust from said stream, means to force the dust entrapped in said pockets during its travel into the furnace, and means to receive any flue-dust in excess of the capacity of said pockets.

3. The combination with a furnace; of a dust collector above the furnace, a pipe into which the dust collector discharges dust and having a spiral portion intermediate its ends, a receptacle at the end of the pipe, means to force charges of dust into the furnace and supplied from said spiral portion as the dust descends by gravity through said pipe to the receptacle.

4. The combination with a reducing furnace; of a dust collector above the top of the furnace, means to discharge dust therefrom by gravity continuously, pockets to entrap the dust during its discharge, means to continuously force the dust collected in said pockets into the furnace, and means to collect and store any dust in excess of that entrapped by the pocket.

5. The combination with a reducing furnace; of a dust collector mounted above the same and having a conical bottom, a down-comer having its entrance centrally within and below the top of the collector, a plurality of pipes extending from above the stock line of the furnace and discharging tangentially into the collector and above the entrance to the down-comer, two pipes connected to the dust collector at its bottom and into which the dust is discharged by gravity, said pipes having spiral portions extending substantially half way around the furnace, a receptacle into which both of said pipes discharge, short substantially vertical pipes forming pockets connected to said spiral portions and means to force the dust entrapped in said pockets into the furnace.

6. The combination with a reducing fur-

nace and charging means therefor; of a dust collector supported above the charging means, a pipe connecting the furnace at a point above the stock line with the collector, 5 a bleeder valve on said pipe, a distributor pipe extending from the bottom portion of the collector to receive flue dust from the collector, a plurality of mechanisms for forcing flue dust into the furnace below its stock line, 10 said mechanisms successively supplied with flue dust by said distributor pipe.

7. The combination with a reducing furnace and a plurality of mechanical means arranged around the furnace to force flue dust into the furnace below the stock line thereof; of means to continuously and automatically conduct the flue dust in a plurality of helical paths on opposite sides of 15 the furnace to said forcing means, said conducting means arranged to maintain the flue dust in the forcing means solely under the direct pneumatic pressure of the furnace gases under all conditions of operation.

25 8. The combination with a reducing furnace and a plurality of mechanical means arranged around the furnace to force the flue dust into it below the stock line thereof; of means to continuously and automatically 30 discharge the flue dust by gravity at different levels to said forcing means while maintaining the dust in said means solely under the pneumatic pressure of the furnace gases, and means below any of the

forcing means to collect any flue dust passing 35 said forcing means and also under the pressure of the furnace gases.

9. The combination with a reducing furnace, of means into which said furnace discharges flue dust from the furnace gases, 40 means to automatically and continuously discharge the flue dust therefrom by gravity, means to entrap separate volumes of flue dust during its discharge from the first mentioned means, and mechanism to positively introduce said separate volumes separately into the furnace below the stock line 45 therein.

10. The combination with a reducing furnace, of means into which said furnace 50 discharges flue dust from the furnace gases, means to automatically and continuously discharge the flue dust therefrom by gravity, means to entrap separate volumes of flue dust during its discharge from the first 55 mentioned means, mechanism to positively introduce said separate volumes separately into the furnace below the stock line therein, and means to collect any flue dust in excess of the entrapped separate volumes. 60

In testimony that I claim the foregoing as my invention, I have signed my name in presence of two subscribing witnesses.

JOHN W. DOUGHERTY.
